PRICE TAG HOLDING MEANS

Charles E. Timmons, Kernville, Calif.

Application February 8, 1933. Serial No. 655,808

2 Claims. (Cl. 40—11)

This invention relates to improvements in price tag holding means and has particular reference to means for holding price tags in an adjustable position relative to a shelf supporting goods to be sold.

A further object is to produce a holder wherein the tag may be moved longitudinally along the shelf so as to be directly beneath the goods to which it refers.

10 An additional object is to produce a price tag holder which is economically manufactured, easy to apply and one wherein the figures may be readily changed from time to time.

Other objects and advantages will be apparent 15 during the course of the following description.

In the accompanying drawing forming a part of this specification and in which like numerals are employed to designate like parts throughout the same,

20 Fig. 1 is a front plan view of a shelf arrangement having my invention applied thereto,

Fig. 2 is an enlarged fragmentary top plan view of one of the supporting rails and a tag holder slidably mounted thereon,

25 Fig. 3 is a fragmentary perspective view of the supporting rail,

Fig. 4 is an enlarged detail cross sectional view of a portion of a shelf showing my invention applied thereto, the supporting rail being in cross section,

30 Fig. 5 is a perspective view of the tag holder,

Fig. 6 is a side elevation of the tag holder,

Fig. 7 is a modified form of tag holder,

35 Fig. 8 is a cross sectional view of a price card, showing the manner of folding an indicia bearing strip thereabout, and

Fig. 9 is a perspective view of the price card showing an indicia bearing strip about to be folded upon the price card.

40 In the grocery business it is essential that means be provided for indicating the sale price of the goods being sold, particularly in grocery stores where the customer helps himself, and owing to the fact that the articles upon the shelves are constantly being moved, increased or diminished, it will be obvious that it becomes necessary to continuously move the price tag in order that it may be directly in front of the goods to which it refers. Applicant has, therefore, devised a novel means of accomplishing this purpose, which consists of a supporting rail mounted beneath the shelf upon which the goods are placed. This rail slidably supports a number of

50 price or tag holders which may be shifted along

the rail so as to lie directly in front and just below the goods.

In the accompanying drawing wherein for the purpose of illustration is shown a preferred embodiment of my invention, the numeral 5 designates shelves as are commonly found in stores. Mounted beneath each of these shelves is a supporting rail 6. This rail is peculiarly formed so as to have an offset front edge 7 and a channel 8 at its rear edge. At 9 I have formed a bead 60 which projects downwardly as best illustrated in Figs. 3 and 4. This rail is fastened to the shelf in any desired manner as for instance by screws 11. In order to support price tags upon this rail, I provide tag holders which consist of a 65 blank having a front plate 12, which is provided with bent ends 13 and 14 to receive and retain a price card in contact with the plate. A tongue 16 prevents the price card from dropping out of the holder. 70

This tag holder has a portion 17 bent at right angles to the plate 12 and provided with spring portions 18 and 19, adapted to engage the upper surface of the offset portion 7 of the rail. A tongue 21 is formed integral with the portion 80

17 and has an offset portion 22, which is adapted to engage the bead 9 (see Fig. 4). The end 23 is received in the channel 8. The modified form shown in Fig. 7, the construction of the card holder is substantially the same with the exception 85

that I have substituted for the plate 12 a hook 24 from which a hanger 26 may be suspended and I have also formed the parts 18 and 19 by bending the metal of the tongue back upon itself, which hanger carries a card holding member 27 which is similar to the plate 12 in its function. The price cards preferably consist of a blank 29 of any desired color and of sufficient 90

length to extend between the bent ends 13 and 14 of the holder. These cards serve to carry indicia strips 31 upon which indicia is printed. The indicia strips are bent as indicated in Figs. 8 and 9, the short end being bent over the top and the long end over the bottom. This arrangement permits several indicia strips to be positioned upon a single card and then the card placed in the holder. 95

It will be apparent that when an arrangement, such as I have illustrated, is in use, that the user may readily place various price cards in each of the holders and may then place the holders on the supporting rail, after which the holder may be moved longitudinally, and that through the construction the holder will be ef- 100

105

110

fectively retained against accidental displacement and will also present a neat appearance.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the character described, a supporting rail having an offset edge, a channel formed on its opposite edge, a bead interposed 15 between said edges, means for securing said sup-

porting rail to a shelf, and a tag holder longitudinally movable on said rail.

2. In a device of the character described, a tag holder including a plate having its end portions bent upon itself to retain a price card, a portion formed at right angles to said plate, a tongue formed integral with said bent portion, an offset portion formed within said tongue, a supporting rail having a channel capable of receiving the end of said tongue, a bead formed in said rail and adapted to lie within the offset portion of said tongue, and an offset portion formed in said rail and capable of being engaged upon its upper surface by a portion of said tag holder.
